COLLAR SUPPORTING DEVICE

James W. Steele, North Kansas City, Mo.

Application October 11, 1957, Serial No. 689,695

2 Claims. (Cl. 223—83)

This invention pertains to laundry accessories and particularly to reinforcing or supporting devices such as are used in bracing and supporting the collar portions of collar-attached garments, such as shirts and the like.

The primary object of my invention is to devise a simple and improved collar bracing and supporting device adapted to be conveniently inserted inside the folds of the collar portions of such garments, and in such position as to protect or reinforce the collar portions and at the same time permit the same to yield into a more or less flatly compacted relation for reducing the space required for bundling or packing purposes.

Accordingly I have devised an improved form of collar support adapted to be constructed of suitable cardboard material and of a size designed to extend an ample distance inside the folds of a garment collar, and so constructed at the front of the collar as to maintain a moderately stiff supporting action while at the same time yielding to a slight degree in the usual handling of the same for packing and wrapping purposes.

It is also an object of the invention to provide a neat and handy construction of attractive design, for lending a becoming appearance to the collar portion of the garment when the device has been placed in its operative position within the folds of the collar.

With the foregoing general object in view, the invention will now be described by reference to the accompanying drawing illustrating one practical and efficient form of construction which I have devised for embodying my improvement, after which the essentially novel features comprising my invention will be set forth in the appended claims.

In the drawing—

Figure 1 is a perspective view of a collar-attached form of shirt having the present improved form of collar-supporting device inserted within the collar portion of said shirt in the required supporting relation thereto;

Figure 2 is a plan view of the collar-supporting device in separate detached relation; and

Figure 3 is a sectional detail view representing a section taken on the line 3—3 of Figure 1 on an enlarged scale.

Collar supporting devices of the type herein involved have been very widely adopted and are in quite general use throughout the garment manufacturing and laundering and cleaning industries for protecting the collar portions of the garment and also preserving its shape or contour throughout the various operations of handling the garment and wrapping and packing the same. While the use of various forms or types of collar supports has grown in favor, one drawback or disadvantage has been the increase in bulk or space required due to supporting action of the collar support when in place within the collar, where its function has been to brace the collar in a more or less upright position. This of course results in a corresponding increase in depth or bulk of the garment, for which allowance must be made in connection with any subsequent handling or packaging proc-

2

esses, thereby involving some practical disadvantage or drawback in connection with those operations where the usual or conventional types of collar supports are used.

Accordingly it is the purpose of my invention to provide an improved design of collar support, of a simple and practical construction which will carry out the essential supporting and bracing function to the necessary extent, and at the same time permit a certain degree of yielding action to allow the garment collar structure to accommodate itself to a somewhat settled or less fully-upright position.

Referring now to the accompanying drawing in detail, the present improved collar-supporting device is illustrated as comprising a strip or section of suitable cardboard or similar material, of relatively stiff but slightly flexible properties, in the form of a strip or band 10 of generally V-shaped contour, as represented in Figure 2. This strip or band is of an appropriate length, so that when inserted between the inner neckband portion 12 and the outer fold portion 14 of the collar 16 of a collar-attached shirt 18, the said strip or band will extend substantially half way around the opposite sides of said collar 16, as clearly shown in Figure 1 of the drawing.

Preferably the upper edge of the strip or band 10 is formed at the middle portion thereof with a notch or recess 20, which is adapted to be positioned at the front or meeting ends of the collar 16 when the band has been inserted within the collar, as represented in Figure 1, in which position the upper outer corners of said notch 20 provide points 21 which are thus suitably designed to engage the crease or turned edge 22 of the collar and thereby operate to hold the meeting end portions of the collar in their proper meeting relation as shown in said Figure 1.

Opposite said notch or recess 20 the strip or band 10 is formed with a relatively wider midportion in which a tongue-shaped portion 24 is produced by a pair of slits 26 cut in upwardly converging relation and terminating some distance below said notch 20. The said tongue-shaped portion 24 thus projects to some distance below the lowermost portion of the bottom edge of the band and is thus shaped to permit a certain degree of relative movement between said tongue portion and the remainder of the band and thereby allow a corresponding degree of yielding or limited settling action of the middle portion of the band as a whole along with the front ends of the collar.

From this description of my improved device, and the manner in which it is adapted to be used as illustrated by the drawing, it will be clear that its use is well adapted to serve the intended purpose, that of producing an appreciably greater degree of compactness of the collar-attached portion of the garment, for bundling and packaging operations, without loss or any diminishing of any of the protective functions of the device as regards shielding and preserving of the lines and folds of the collar structure throughout the folding and subsequent handling of the garment.

It is moreover pointed out that the form of the device and its initial state adapt it for ready insertion into place within the collar early in the finishing process and prior to the folding operation, where it remains throughout the subsequent operations of folding and the later bundling and packing of the garment.

It will also be apparent and understood that the bracing tongue element may be of any preferred design type adapted to lend an attractive and becoming appearance to the collar front of the finished garment. Obviously, therefore, various different tongue designs may be formed by different types of slit arrangements, the essential or primary object being to provide either a single or multiple tongue structure operative to permit a limited degree

of settling movement of the middle portion of the supporting band along with the front end portions of the collar, as herein set forth.

From the foregoing therefore it will be quite manifest that I have devised a practical and efficient type of device for fulfilling the general purpose of the invention; and while I have illustrated and described one suitable form of embodiment of the device in detail, I desire to reserve the right to make such obvious modifications as may fairly fall within the scope of the appended claims.

Having thus described my invention, what I claim is:

1. A collar supporting device for collar-attached shirts, comprising a band or strip of relatively stiff and slightly flexible material, of a length sufficient to span the space between the front meeting end portions of the collar and also project between the inner and outer folds thereof a distance substantially halfway around each of the opposite sides of the collar, the middle portion of said band or strip being cut by converging slits forming a tongue-shaped portion projecting from a location near the upper margin of the band to some distance below the lower edges of the band at the opposite sides of said tongue shaped portion.

2. A collar supporting device for collar-attached shirts, comprising a band or strip of relatively stiff and slightly flexible cardboard material, of a length sufficient to span the space between the front meeting end portions of the collar and also project between the inner and outer folds thereof a distance substantially halfway around each of the opposite sides of the collar, the upper margin of the middle portion of said band or strip having a notch providing points for engaging the inner turned edge of the collar, and said middle portion of the band being also cut by a pair of slits converging toward said notch and forming a tongue-shaped member extending from a location adjacent said notch to some distance below the lower edges of the band at the opposite sides of said tongue-shaped member.
